DRAUGHT EXCLUDING ARRANGEMENT
FOR DOORS

Robert I. Bach, Sondeled, Norway

Application April 4, 1949, Serial No. 85,339
In Norway April 19, 1948

3 Claims. (Cl. 20—67)

1

The present invention relates to a draught excluding arrangement for doors of the type which are to be used without door sills and the object of the invention is to provide an improved arrangement of this kind wherein the draught excluding means is effectively held against the floor in the closed position of the door.

A further object of the invention is to provide a draught excluding arrangement which is located within the cross section of the door, whereby the door retains its smooth surface on both sides, and at the same time forms an extension thereof.

The draught excluding arrangement according to the invention is of the type comprising a spring loaded flap or strip mounted on the bottom of the door and adapted to cooperate with a stationary impact member in such a manner that said flap or strip, in the closed position of the door, is held pressed against the floor, and the invention is characterised in that the flap or strip consists of a strip of elastic material provided along one edge with a thickened portion through which is passed a shaft by means of which the flap or strip is hingedly supported in a recess or channel at the lower end of the door.

In order that the invention may be more clearly understood one particular embodiment thereof will now be described, by way of example, with reference to the accompanying drawing wherein:

Figure 1 is a side elevation of the lower part of a door provided with an arrangement according to the invention,

Figure 2 is a section on the line II—II of Figure 3,

Figure 3 is a plan view of the under-side of a portion of the door, and

Figure 4 is an elevational view of the lower part of a door-frame seen from the door-way.

Referring to the drawing 1 denotes the lower end of a door to the under side of which is suitably secured a member 2 having a channel-shaped cross section, with the channel or recess 3 facing downwards, and a width and length corresponding to the thickness and width respectively of the door 1. The channel or recess 3 of the channel-shaped member 2 is closed at both ends by means of plates 4 secured to said member by means of screws 5 and 6. A shaft 7 extends longitudinally in the channel 3 adjacent to one of the side walls thereof and is rotatably supported in said plates 4. At the side of the door opposite to the hinged side one end of the shaft 7 projects outside the end plate 4 and is bent

2

into the form of a crank 8, 9 with the part 9 of the crank extending outwardly beyond the edge of the door and parallel with the shaft 7 and forming a bearing for a rotatable roller 10 of rubber or the like.

On the shaft 7 is secured a draught excluding hinged flap or strip 11 of rubber or a similar resilient material. The flap or strip 11 is provided with a thickened portion 12 along the edge thereof and said thickened portion has a longitudinal bore through which passes the shaft 7 which forms part of the hinge on which the flap or strip is mounted. The free edge of the hinged flap or strip 11 opposite to said thickened portion 12 is bevelled so that said bevelled edge is positioned approximately parallel with the floor surface in its lowered position (see Figure 2).

In order to increase the elasticity of the free edge portion of the flap or strip 11 a longitudinal recess or groove 13 is provided at a small distance from the free edge which recess weakens the resistance of the strip to bending at this point.

At a suitable distance from each of the ends of the flap or strip 11 a strap or plate 14 is bent around the thickened portion 12 and the ends of said strap or plate 14 are interconnected by a screw 15 inserted from the under side of the strip 11. The length of said strap 14 is such that the screw 15 is situated approximately at the centre of the width of the flap or strip 11. On the upper free end of the screw 15 is screwed one end of a tightly wound helical spring 16 the opposite free end of which normally projects into a bore 17 extending from the bottom of the channel 3 through member 2 and into the door 1. In order that the spring 16 should slide unobstructed into and out of said bore 17 an eyelet-shaped sleeve 18 is secured in the lower end thereof.

In the opened position of the door the flap or strip 11 is held in the channel 3 in a horizontal position (as shown in Figure 1) by the springs 16 the bending momentum of which is strong enough to swing the strip when released into said position.

At the lower end of the frame 19 of the door (Figure 4) with which the outer edge of the door 1 cooperates, a recess 20 is provided the limiting surface of which is formed by a ferrule strip 21 which forms a downwardly inclining surface with which the roller 10 on the end of the lever 8 cooperates.

When the door is closed the roller 10 runs down the inclined surface 21 which presses the roller 55 downwards whereby the shaft 7 is rotated and

the flap or strip 11 is swung downwards until the free bevelled edge surface of said flap or strip rests against the floor 22. The downwardly swinging movement of the flap or strip 11 is opposed by the springs 16 which are thereby partly drawn out of the bores 17 and simultaneously bent as shown in Figure 2. When the door is again opened the roller 10 runs up the inclined surface 21 and the flap or strip 11 swings back into the position shown in Figure 1 under the action of the spring 16 which automatically straighten.

As will be understood the channel or recess 3 may be arranged in the lower end of the door proper, but by providing a separate member 2 adapted to be secured to the bottom of the door the draught excluding device may be produced separately and mounted on a door independent of the construction of the door, or on existing doors which normally cooperate with a door sill which is to be removed.

The means effecting the downwardly swinging movement of the flap or strip 11 may be constructed in other suitable manner dependent on the type of door on which the device is mounted, for example, with sliding doors the roller 10 on the lever 8 may be arranged on the shaft 7 so as to run over inclined surfaces extending in the direction of movement of the door.

I claim:

1. In a draught excluding arrangement for doors, in combination a door body provided on its under surface with a downwardly open channel and with at least one upwardly extending bore communicating with the top of the channel, a flap of elastic material provided with a thickened portion along one edge thereof, a shaft passing through the thickened portion of the flap and having its respective ends journaled at the ends of the channel, a crank extending outwardly from the shaft at the outer edge of the door, a roller on said crank, at least one helical spring having one end secured to the flap and its other end slidably arranged in the bore and normally arranged in a straightened position within the bore so as to hold the flap elevated, and stationary means on the door frame for

cooperating with the roller in the closed position of the door in order to hold the flap pressed downwardly against the floor and against the action of the spring.

- 5 2. A draught excluding arrangement for doors including a separate member secured to the lower end of the door and forming an extension thereof and provided with a channel and also provided in its upper wall and substantially medially there-
10 of with at least one upwardly extending bore, a flap of elastic material arranged in said channel and provided along one edge with a thickened portion, a shaft engaged with said thickened portion and rotatably mounted within said chan-
15 nel, a crank extending from the end of the shaft at the outer edge of the door, a roller supported on said crank, at least one helical spring having one end secured to the flap and the other end slidably engaged in the bore and normally re-
20 tained in such position by its inherent straightening action for holding the flap within the channel, and stationary means on the door frame cooperating with the roller in the closed position of the door in order to hold said flap pressed down-
25 wardly against the floor and against the action of the spring.

3. A draught excluding arrangement as claimed in claim 1 wherein at least one strip is bent around the thickened portion of the hinged flap, a screw interconnecting the ends of the bent strip with the outer end of the screw projecting beyond the flap in order to form an anchoring means for the adjacent end of the helical spring.
